(57) CLAIM

The ornamental design for a concealed weapon panel, as shown and described.

DESCRIPTION

FIG. 1 a perspective view of a concealed weapon panel, showing my new design;

FIG. 2 is a front view of a concealed weapon panel;
